[57] CLAIM

The ornamental design for a vehicle lamp lens, as shown and described.

DESCRIPTION

FIG. 1 is a perspective view of the vehicle lamp lens of the present invention wherein the broken lines are for illustration purposes only and form no part of the claimed invention;

FIG. 2 is a view of the lens taken in the direction of the arrow "2" of FIG. 1;

FIG. 3 is a side elevational view thereof, with the opposite sides being a mirror image;

FIG. 4 is a rear view of the lens taken in the direction of the arrow "4" of FIG. 3;

FIG. 5 is a top plan view thereof, with the bottom being a mirror image;

FIG. 6 is a cross sectional view taken along the line 6—6 of FIG. 2; and,

FIG. 7 is a cross sectional view taken along the line 7—7 of FIG. 2.
